GRINDING MILL

Richard Zückert, Chard, England, assignor of
one-half to L. & C. Hardtmuth, Inc., Blooms-
bury, N. J., a corporation of New Jersey

Application November 8, 1948, Serial No. 58,973
In Great Britain November 27, 1947

11 Claims. (Cl. 241—107)

1

This invention relates to grinding mills, especially, though not restrictively, to mills for grinding graphite for use in the manufacture of pencils.

Various forms of wet grinding mill are known for this purpose; for example in one form a grinding stone is superposed on, and rotated eccentrically in relation to, a second grinding stone which is free to rotate about its own axis as a result of the friction between the contiguous surfaces of the two stones, the mixture of water with graphite to be ground being fed axially through the upper stone and passing radially outwards between said contiguous surfaces. The output of this mill is small.

In another form, a high speed mill, the grinding stones are coaxial, their contiguous surfaces are formed with corresponding grooves and ridges so that in cross-section the grinding surface of each stone is of zig-zag configuration, one stone being fixed and the other rotated and the mixture of water with graphite being fed in axially through the rotary stone.

In still another mill a plurality of grinding blocks are urged radially against the periphery of a rotary grindstone, the graphite being fed to the contiguous surfaces of the blocks and stone through passages formed in the blocks. In yet another arrangement a rotary grinding stone is formed with an internal frusto-conical grinding surface and is fitted on to a correspondingly shaped fixed grinding stone, the mixture of water with graphite being fed axially through the rotary stone.

According to the present invention a grinding mill comprises a body presenting an inner peripheral grinding surface, a carrier arranged to be rotated within the body and at least one grinding block disposed on said carrier so as to be slidably radially with respect thereto and bear against the inner peripheral grinding surface of the body under the influence of centrifugal force, the body being arranged for the introduction thereinto of the material to be ground and for the egress of the ground material.

It is desirable that a plurality of grinding blocks should be slidably mounted on the carrier which may be co-axially arranged with respect to the grinding surface of the body, but, prefer-

2

ably, is arranged eccentrically so that material lying in the spaces between adjacent blocks is subjected to pressure as it approaches the exit from the body.

5 The invention is illustrated by the accompanying drawings in which:

Figure 1 is a partly sectional side elevation of one form of grinding mill, the section being taken on the line I—I, Figure 2;

10 Figure 2 is an end elevation thereof, as seen from the left, Figure 1, with the end plate removed;

Figures 3 and 4 are sectional end views on the lines III—III and IV—IV, respectively, Figure

15 1; and

Figures 5 and 6 are diagrammatic views of two arrangements for carrying out the grinding of, e. g., graphite for use in the manufacture of pencils.

20 As depicted in Figures 1 to 4, the mill has a cylindrical body *a* supported by feet *b*, *b* and is formed with an inlet *c* and an outlet *d* for e. g. a mixture of graphite and water, the inlet *c* and the outlet *d* leading to and from chambers

25 *e* and *f*, respectively, in the body *a*, as shown in Figure 4. Within the body *a* a plate or diaphragm *g* is secured by screws *h*, *h* and serves to divide the chambers *e* and *f* (at the right-hand end of the body *a*, Figure 1) from the grinding space (at the left-hand end of the body *a*, Figure 1). The diaphragm *g* is formed with an inlet passage *j* and an outlet passage *k* (Figure 3) communicating with the chambers *e* and *f*, respectively.

30 35 Within the body *a*, at the side of the diaphragm *g* remote from the chambers *e* and *f* a solid cylindrical carrier *m* (Figures 1 and 2) is mounted on the projecting end of an eccentric shaft *n* carried in a bearing *o* (Figure 4), the

40 diameter of the carrier *m* and the eccentricity of the shaft *n* being such that the periphery of the carrier *m* and the inner periphery of the body *a* are tangential at the top of the latter. A plate *p* applied to the end of the body *a* closes, in 45 said body, the grinding space, between said plate and the diaphragm *g*.

For about one half of its angular extent that part of the inner peripheral wall of the body *a* corresponding with the grinding space has an 50 arcuate inset *q* (Figure 2) of hard porcelain, fire

clay, siliceous stone or the like to present a grinding surface and the carrier *m* is formed with recesses *r* to receive grinding blocks *s* of similar material. The operative face of each block *s* may be of the same curvature as the inner peripheral surface of the grinding inset *q* (i. e. of the same radius as the inner peripheral wall of the body *a*) and, preferably, the leading end of said operative face is of smaller radius, as indicated at *t*, Figure 2, for a purpose which will appear hereinafter.

As shown in Figure 3, the inlet passage *j* to the grinding space begins at about 20° (in the direction of rotation of the body *m*) from the position where the periphery of the body *m* and the inner periphery of the body *a* are tangential to one another and has an angular extent of about 120° and the outlet passage *k* extends for about 20° up to said position.

For use the inlet *c* is connected with a source of supply (not shown in Figures 1 to 4) of a mixture of water and graphite and the shaft *n* is rotated by means of a belt pulley *u* mounted thereon and driven from a prime mover, not shown. Centrifugal force acting on the blocks *s* as a result of the rotation of the carrier *m* causes said blocks to move radially outwards and bear against the inner peripheral face of the body *a*, and, on account of the eccentric movement of the carrier *m* within the body *a* the device acts as a pump and the arrangement is such that some of the graphite drawn through the inlet *c* and passage *j* into a space *v* between two adjacent grinding blocks *s* passes, and is ground, between the operative face of the trailing block *s* and the inner peripheral surface of the inset *q*, passes to the succeeding space and is ground by the succeeding block *s*, and so on, the graphite being carried round gradually as the carrier *m* is rotated and being compressed as the volume of the spaces *v* is reduced, the pressure thus created serving to expel ground graphite through the outlet passages *k* and *d*. The entrance of the graphite to the operative face of a block *s* being facilitated by the space at *t*.

It has been stated above that the operative face of each block *s* may be of the same curvature as the inner peripheral surface of the body *a*. This indicates that in general there will be adequate surface contact between those two parts during the revolution of the body, but, as the pressure on the liquid increases during the second half of a revolution of the eccentric body it is desirable that the surface contact should be superior during said second half revolution, for which purpose the curvature of the operative face of each block should approximate as nearly as possible that of the inner peripheral wall of the body when the block is at about 45° in rear of the position at which said surface and wall are tangential.

In order to ensure thorough grinding of the graphite repetition of the operation is desirable, for which purpose, shown by way of example in Figure 5, the inlet *c* and outlet *d* may be connected with a storage vessel *w*, in which the liquid mixture may be stirred to prevent precipitation and from which it may be drawn and passed again through the mill. Alternatively, as shown in Figure 6, a plurality of mills may be connected in series so that the output from one mill passes direct to the inlet of the next mill of the series and so on.

By either of these means all the graphite (even that which, in the first instance, might have

been carried round in a space *v* and thus escaped being ground) will, in time, be subjected to the desired grinding operation.

If desired the body *a* and/or the vessel *w* may be water jacketed but it will usually be found sufficient to cool the liquid as it passes to and/or from the vessel *w* or when a series of mills is employed as it passes from one mill to the next.

In some cases springs may be provided to ensure contact of the operative faces of the blocks *r* with the inner peripheral surface of the body *a* so as to ensure that pumping action will commence as soon as the carrier *m* is rotated.

Although the inlet and outlet passages *j* and *k* provide for the entrance of the liquid into the grinding space, and its exit therefrom, in a direction parallel with the axis of rotation of the carrier *m*, such entrance and exit may be arranged in the radial direction, but the former is preferable as it enables the maximum grinding surface to be presented in a mill of any given size.

If desired, pressure (positive and negative) means may be provided for facilitating the introduction of the material into, and its exit from, the body *a*, such pressure means may be co-ordinated with the rotation of the carrier so that impulses occur when spaces between adjacent blocks are opposite the entrance and exit passages.

A grinding mill constructed in accordance with this invention is adapted for operation at high speed, the graphite is not subjected to anything but simple grinding action, i. e. it is never subjected to beating, stamping or other impact as in some of the known mills and yet the improved mill has a greater output than the known forms of mere grinding mills.

I claim:

1. A grinding mill comprising a cylindrical body presenting an inner peripheral abrasive surface, a carrier mounted to rotate within said body about an axis eccentric to the axis of the body, at least one abrasive block mounted in said carrier and slidably radially with respect thereto so as to bear against the grinding surface under the influence of centrifugal force, and an inlet and outlet into the grinding space of the body located on opposite sides of a radial plane through the point of closest approach of the carrier to the body.
2. A grinding mill as claimed in claim 1 having a plurality of radially slidable blocks.
3. A grinding mill as claimed in claim 2, in which the inlet to the grinding space extends from about 20°, in the direction of rotation of the body, from such point to about 140° from said point and an outlet extending through about 20° up to said point.
4. A grinding mill as claimed in claim 3, wherein the operative face of each abrasive block has the same curvature as the inner peripheral surface of the body.
5. A grinding mill as claimed in claim 4, wherein in the leading end of the operative surface of each abrasive block is of reduced radius.
6. A grinding mill as claimed in claim 1, in which the inlet to the grinding space extends from about 20°, in the direction of rotation of the body, from such point to about 140° from said point and an outlet extending through about 20° up to said point.
7. A grinding mill as claimed in claim 6, wherein in the operative face of each abrasive block has

the same curvature as the inner peripheral surface of the body.

8. A grinding mill as claimed in claim 7, wherein the leading end of the operative surface of each abrasive block is of reduced radius.

9. A grinding mill as claimed in claim 1, wherein the operative face of the abrasive block has the same curvature as the inner peripheral surface of the body.

10. A grinding mill as claimed in claim 1, 10 wherein the leading end of the operative surface of the abrasive block is of reduced radius.

11. A grinding mill as claimed in claim 1 in which said surface and block are of a material selected from the group consisting of hard porcelain, fire clay and siliceous stone. 15
